UNITED STATES PATENT OFFICE.

HOWARD M. BARBER, OF WESTERLY, RHODE ISLAND, ASSIGNOR TO C. B. COTTRELL & SONS COMPANY, OF WESTERLY, RHODE ISLAND, A CORPORATION OF DELAWARE.

WEB SLACK PREVENTER FOR MULTICOLOR PERFECTING PRINTING PRESSES.

Application filed October 31, 1925. Serial No. 65,976.

In multi-color web perfecting printing presses where a greater number of colors are printed on one side of the web than on the other, for instance where two colors are printed by the first printing unit on one side of the web and four colors are printed by the second printing unit on the other side of the web, and where a common impression cylinder is provided in each printing unit, it has been customary to make the diameter of the impression cylinder of the first printing unit the same as the plate cylinders of that unit and the diameter of the impression cylinder of the second printing unit a multiple of the diameters of the impression cylinder of the first printing unit and the plate cylinders of the second printing unit.

This arrangement has made it difficult to produce clean and sharp printing in the second printing unit because of a tendency to slur, owing to the formation of a slack in the web between the two printing units.

I have discovered that if the impression cylinders of the two units be made of the same diameters and their bearer diameters made the same, this slack in the web between the printing units is eliminated, slurring in the second printing unit is prevented and clean and sharp printing is ensured.

A practical example of my invention is represented in the accompanying drawings, in which the plate and impression cylinders of the first printing unit are denoted by 1, 2 and 3 and the plate and impression cylinders of the second printing unit are denoted by 4, 5, 6, 7 and 8. The web which

is passed through the two units is denoted by 9.

The plate cylinders of the two units are the same diameters and the impression cylinders of the two units are the same diameters, in the present instance twice the diameters of the plate cylinders. It will be understood that the bearer diameters of the two impression cylinders must be the same to prevent the formation of slack in the web and to ensure clean and sharp printing in the second printing unit.

What I claim is:—

1. In a multi-color web perfecting printing press, two printing units arranged to print more colors on one side of the web than on the other side thereof, the bearer diameters of the plate cylinders of both printing units being the same and the bearer diameters of the impression cylinders of both printing units being the same but multiples of the bearer diameters of their plate cylinders.

2. In a multi-color web perfecting printing press, two printing units, one arranged to print two colors on one side of the web and the other to print four colors on the other side of the web, the bearer diameters of the plate cylinders of both printing units being the same and the bearer diameters of the impression cylinders of both printing units being the same but twice the bearer diameters of their plate cylinders.

In testimony, that I claim the foregoing as my invention, I have signed my name this 28th day of October, 1925.

HOWARD M. BARBER.
